(57) **CLAIM**

The ornamental design for an angle set knife sharpener, as shown and described.

DESCRIPTION

FIG. 1 is an isometric view of the design.

FIG. 2 is a left side elevational view of the design of FIG. 1.

FIG. 3 is a right side elevational view of the design of FIG. 1.

FIG. 4 is a top plan view of the design of FIG. 1.

FIG. 5 is a right side view of the design of FIG. 1; and, FIG. 6 is a left side view of the design of FIG. 1.

The broken line showings of the angle set knife sharpener are provided for purposes of environment and form no part of the claimed design.
